N. Y., a corporation of Delaware

Application November 15, 1939, Serial No. 304,507

15 Claims. (Cl. 62—118)

This invention relates to refrigeration, and more particularly to refrigeration apparatus or systems of the non-continuous or intermittent or periodic type.

The purpose of this invention is to improve the operation of systems of this type whereby the periods of refrigerant evaporation, which alternate with periods of expulsion of refrigerant from absorbent, may be effectively controlled. This is accomplished by embodying in the intermittent system circuit connections whereby a refrigerant evaporation period will start at the conclusion of a refrigerant expulsion period only when a certain operating condition is satisfied. In the embodiment of the invention disclosed, a heat operated device is provided which permits refrigerant evaporation to take place when heat is supplied to a part of the system other than the usual heat receiving part. The particular type of intermittent system provided may be operated alone, and, in addition, is particularly suited for operation in combination with a heat operated refrigerating system of a continuous type in which a more or less steady refrigerating effect may be produced. The heat receiving parts of the continuous system, and intermittent system may be arranged for heating by a common source of heat, and the intermittent refrigerating system may be so constructed and arranged that the evaporation periods of the intermittent system can take place even when the heat receiving parts of both systems are supplied with heat by the common heat source, whereby shutting off of the heat supply to the continuous system is avoided when additional refrigeration is desired from the intermittent system. With this arrangement, the intermittent system is available to produce intense refrigeration for comparatively short periods of time when such refrigeration is desired, that is, the continuous system may be arranged to carry the normal refrigerating load with the intermittent system taking care of the peak loads.

The invention, together with the above and other objects and advantages thereof, will be more fully understood upon reference to the following description and the accompanying drawings forming a part of this specification, and of which:

Fig. 1 illustrates more or less diagrammatically an intermittent refrigeration system embodying the invention shown in connection with a continuous refrigerating system, parts of both systems being shown in section to illustrate the invention more clearly; and

Fig. 2 is a sectional view, taken on line 2—2 of

Fig. 1, to illustrate more clearly the evaporator of the intermittent system.

In Fig. 1 the improved intermittent refrigerating system has been shown in connection with a continuous refrigerating system of a uniform pressure absorption type containing an inert gas or auxiliary agent. A system of this type includes a generator 10, a condenser 16, an evaporator 18, and an absorber 22 which are inter-connected in a manner well known in the art and which will now be briefly described. The system contains a solution of refrigerant in absorption liquid, such as ammonia in water, and an inert gas or auxiliary agent, such as hydrogen.

The generator 10 includes an outer shell 11 within which extends a flue 12 arranged to be heated in any suitable manner, as by a gas burner 13. A conduit 14 extends upwardly from the upper end of generator 10 and is provided with heat radiating fins 15 to form an air-cooled rectifier. The upper end of the conduit 14 is connected to the condenser 16 which is provided with cooling fins for air cooling.

The lower end of condenser 16 is connected by a conduit 17 to the evaporator 18 which may be of any well-known type. The evaporator 18 is here shown as a hollow vessel which is provided with liquid distributing trays, and the conduit 17 terminates in the upper part of the vessel.

A conduit 19 connects the lower end of evaporator 18 with one passage of a gas heat exchanger 20. The other end of this passage is connected by a conduit 21 with the lower part of the absorber 22. A conduit 23 connects the upper part of the absorber with one end of a second passage of heat exchanger 20, and a conduit 24 connects the opposite end of this passage with the upper part of the evaporator 18. A drain conduit 25 connects the second-mentioned passage of the gas heat exchanger with the lower part of the absorber 22, and a vapor vent 26 connects the condenser 16 with the first-mentioned space of the heat exchanger 20.

A conduit 27 extends downwardly from the lower part of the absorber 22 to the inner conduit of a liquid heat exchanger 28. The opposite end of this conduit is connected to a pipe 29 which is wound in the form of a coil 30 around and in good heat exchange relation with the lower end of flue 12 and thence extends upwardly and communicates with the upper part of generator 10. A pipe 31 connects the lower part of the generator with an end of the outer conduit of the liquid heat exchanger 28, and a conduit 32 connects the opposite end of this conduit with the upper part

of absorber 22. The absorber 22 may be cooled in any suitable manner well known in the art, as by cooling fins or a cooling medium which is circulated in heat transfer relation with the absorber.

The apparatus thus far described constitutes a continuous heat operated absorption refrigerating apparatus of a well known type, the operation of which will be briefly described. Heat is applied by the burner 13 to the generator 10 whereby refrigerant vapor is expelled from solution and flows upwardly through the conduit 14 into the condenser 16 in which it is liquefied. The liquid formed in the condenser 16 flows through conduit 17 to the upper part of evaporator 18. In the evaporator 18 the liquid evaporates and diffuses into an inert gas, such as hydrogen, which enters through the conduit 24, with consequent absorption of heat from evaporator 18 and its surroundings, thereby producing a refrigerating effect. The rich gas mixture of refrigerant and inert gas formed in the evaporator 18 flows therefrom through the conduit 19, the heat exchanger 20, and the conduit 21 into the lower part of absorber 22.

In the absorber the rich gas mixture flows counter-current to weak absorption liquid which enters through conduit 32. The absorption liquid absorbs refrigerant from the inert gas, and inert gas weak in refrigerant flows from the absorber 22 and returns to the evaporator 18 through the conduit 23, heat exchanger 20, and conduit 24. The enriched absorption liquid flows from the absorber 22 through the conduit 27, liquid heat exchanger 28 and conduit 29 to the coil 30. Due to heating by burner 13, liquid is raised in coil 30 and the vertically extending conduit connected thereto into the upper part of generator 10 by thermosiphon action. The weak absorption liquid flows from the lower part of generator 10 through conduit 31, liquid heat exchanger 28, and conduit 32 to the upper part of absorber 22. Since liquid is introduced into the generator 10 at a point above the level at which conduit 32 discharges into the absorber 22, liquid will flow from the generator to the absorber by gravity.

In accordance with this invention, a continuous heat operated refrigerating system of the above type may be combined with an intermittent absorption refrigerating system which is particularly adapted for such combination and also embodies improvements which make for better operation when employed alone. The intermittent system includes a generator 40 in the form of a coil wound around a portion of flue 12 within generator 10 of the continuous refrigerating system. A conduit 41 connects the upper end of generator 40 with a standpipe 42. The upper part of standpipe 42 is in heat transfer relation with fins 15 to provide an air-cooled rectifier for the intermittent system. The standpipe 42 is connected at its upper end to condenser 43 having heat transfer fins to provide for air cooling. A conduit 44 is connected to the opposite end of the condenser 43 and extends downwardly and then upwardly in the form of a loop to communicate with the upper part of one section 45 of an evaporator 46.

As shown most clearly in Fig. 2, each section of the evaporator 46 includes a vessel having vertical legs 47 and 48, an upper cross leg 49, and a lower cross leg 50. A partition 51 divides the lower cross leg into two parts 50a and 50b. The conduit 44 is connected to the upper part of vertical leg 47 and a conduit 52 connects the part

50a of cross leg 50 and the upper part of vertical leg 48. A conduit 53 connects the part 50b of cross leg 50 and the upper part of vertical leg 47 in the adjacent section of the evaporator unit. All of the evaporator sections are connected together in the manner just described. In addition, vapor conduits 54 connect together the upper cross legs 49 of the several evaporator sections.

10 A conduit 55 is connected to the lower cross leg 50 of the last evaporator section and extends upwardly to communicate with the upper part of a vessel 56. A conduit 57 is connected to the upper horizontal leg 49 of the last unit and extends first downwardly and then upwardly to provide a liquid trap having legs 58 and 59. The leg 59 is connected to a conduit 60, which in turn is connected to the upper part of an absorber 61. A conduit 62 is connected to the lower part 15 of the absorber 61 and the vertically extending portion thereof is connected to conduit 57 at a region between the evaporator 46 and the leg 58 of the liquid trap. A conduit 63 extends downwardly from vessel 56 and thence upwardly and 20 is connected to conduit 62 at a point somewhat above the level at which conduit 55 is connected to vessel 56.

A conduit 64 extends from the bottom of absorber 61 and is connected to the lower end of a coil 65 which is arranged to be heated in any suitable manner, as by an electric heating element 66, for example. A conduit 67 extends upwardly from the coil 65 and terminates within a vessel 68. A conduit 69 connects the lower part of vessel 68 and an intermediate point of leg 59. A conduit 70 is connected to the upper part of vessel 68 and to an ejector 71. A conduit 71 connects conduit 70 and the upper part of vessel 56.

25 A conduit 72 at its upper end extends into absorber vessel 61 and at its lower end is connected to the inner conduit of a liquid heat exchanger 73. The other end of this inner conduit is connected to the lower end of the generator coil 40. The lower end of standpipe 42 is connected to an outer conduit of the heat exchanger 73, and a conduit 74 connects the other 30 end of the outer conduit to the upper part of absorber 61. The ejector 71 is connected in the conduit 72. A float 75 is provided within absorber 61 and is dimensioned so as to substantially cover the entire surface of the liquid contained therein. The upper end of conduit 72 within absorber 61 is disposed at a level slightly below the upper end of conduit 67 in vessel 68 and approximately at the same level as the lower ends of legs 58 and 59. The conduit 69 is connected to the leg 59 at a point somewhat above this level. A conduit 76 connects the upper part of standpipe 42 and the leg 59.

35 The above described continuous system may be arranged to produce refrigeration at a substantially constant rate. This rate can of course be varied by changing the quantity of heat supplied to generator 10 by the burner 13. However, in order to be able to produce a much greater refrigerating effect for short periods of time, the intermittent system is provided, the operation of which will now be described.

The absorber 61 of the intermittent system 40 contains a solution of refrigerant in an absorbent, such as ammonia in water, for example. This solution is also present in generator coil 40, and, due to the application of heat to this coil from the flue 12 during the normal operation of the continuous system, refrigerant is ex-

elled from solution and flows upwardly through conduit 41 and the upper part of standpipe 42 into condenser 43. The absorption liquid is raised in the conduit 41 by thermosiphon action and flows downwardly through the standpipe 42, liquid heat exchanger 73 and conduit 74 to the absorber 61. The refrigerant is liquefied in condenser 43 and flows through conduit 44 to the first section 45 of the evaporator 46. The liquid flows into leg 47 and the part 50a of cross leg 50 which is connected thereto. The liquid also flows into conduit 52, and, as soon as leg 47 is filled up to the level indicated in Fig. 2, liquid starts to flow into leg 48. As soon as this leg is filled to the level indicated in Fig. 2, the liquid flows through conduit 53 to the next section of the evaporator which is filled with liquid in the same manner as the first section. Eventually all of the sections are filled with liquid refrigerant.

During this time, legs 58 and 59 of the liquid trap have been filled with liquid which stands at the same level as the liquid in absorber 61 since leg 59 is in communication with the absorber through conduit 64, coil 65, conduit 67, vessel 68 and conduit 69. By the time the evaporator 46 has been filled with liquid refrigerant, the level of the liquid in absorber 61 has dropped to the upper end of conduit 72, due to the expulsion of refrigerant from the absorbent, and hence no more liquid is supplied through conduit 72 to generator 40 and the expulsion of refrigerant from absorbent ceases, thereby terminating a vapor expulsion period, although heat continues to be supplied to coil 40. When circulation of absorbent in the generator 40 ceases, the supply of hot weak solution to the absorber 61 through the conduit 74 also ceases and the absorber begins to cool. This, coupled with the fact that a small amount of absorption at the liquid surface in the absorber takes place, causes a reduction in the pressure existing therein, whereby the liquid in the legs 58 and 59 of the liquid trap is forced upwardly through leg 59 and into the absorber. This produces an unobstructed connection between the vapor space at the top of the evaporator 46 and the vapor space at the top of the absorber 61, whereby the same pressure exists in both of these vessels. Hence it is impossible for refrigerant vapor to force the liquid downwardly in conduit 62 and refrigerant vapor cannot enter the absorber through this conduit. Since the float 75 covers substantially all of the liquid surface in absorber 61, practically no absorption will take place and the intermittent system will be inactive at the conclusion of a refrigerant expulsion period.

When it is desired to produce added refrigeration in addition to that produced by evaporator 46 of the continuous system, an absorption period of the intermittent system is initiated by heating the coil 65 by the heating element 66. This coil is filled with liquid and heating thereof raises liquid upwardly into vessel 68 by vapor liquid lift action, thereby increasing the pressure in this vessel. Due to this increase of pressure in vessel 68, liquid is forced therefrom through conduit 69 to leg 59 of the liquid trap, thus filling the trap with liquid and establishing liquid columns in legs 58 and 59 and conduit 76, thereby blocking off the free communication between the vapor spaces of evaporator 46 and absorber 61. The shortest liquid column is formed in leg 59 and liquid flows therefrom through conduit 60 into absorber 61. A small amount of absorption takes place at the liquid surface in absorber 61

around the edges of the float, whereby the pressure in the absorber is reduced, and the tendency of the liquid refrigerant in evaporator 46 to boil or evaporate causes the pressure in the evaporator to increase. This difference in pressure cannot now be equalized through legs 58 and 59 since the liquid columns are formed therein, and hence the pressure difference existing between evaporator 46 and absorber causes the liquid in conduit 62 to be pressed downwardly and into the absorber 61. When the liquid column in conduit 62 is lowered sufficiently, refrigerant vapor passes into the absorber through this conduit from the evaporator 46 and the absorption liquid absorbs the refrigerant vapor. This absorption of the refrigerant vapor reduces the pressure in the intermittent system, thus increasing the rate at which refrigerant evaporates in the evaporator 46. Due to the large quantity of liquid refrigerant stored in the evaporator, a very great refrigerating effect can be rapidly produced when a refrigerant evaporation period is initiated.

The absorption of refrigerant vapor by the solution in absorber 61 causes the level of the liquid therein to rise above the upper end of conduit 72. By providing the ejector 77 enriched absorption liquid is prevented from flowing from absorber 61 to generator 40 during the period of refrigerant evaporation. If enriched absorption liquid were permitted to flow into generator 40 from absorber 61 through conduit 72 and liquid heat exchanger 73, the pressure in the intermittent system would rise and prevent evaporation of liquid in the evaporator 46. As shown, however, vapor in the upper part of vessel 68 flows through conduit 70 to ejector 77 and liquid in absorber 61 is prevented from flowing through conduit 72 by thermosiphon action. While heating element 66 is heating coil 65, therefore, a vapor lock is formed in conduit 72 by ejector 77 to prevent absorption liquid reaching generator 40 from absorber 61 during a refrigerant evaporation period.

When the need for additional refrigeration by the intermittent system no longer exists, heating of coil 65 is stopped. With heat no longer supplied to coil 65 no liquid and vapor flow into vessel 68 by vapor liquid lift action and the liquid in legs 58 and 59, which has been maintained by the supply of liquid, blows through and free communication between vapor spaces of the evaporator 46 and absorber 61 is established. Refrigerant vapor now cannot enter the absorber 61 through conduit 62 and absorption ceases, terminating the refrigerant evaporation period.

The vessel 56 and the conduits associated therewith are provided to remove absorption liquid which may find its way into the evaporator 46, particularly during shipment of the apparatus when it may be turned upside down. The amount of liquid charged into the intermittent system is so chosen with respect to the volumes of the various vessels and conduits that, if the evaporator 46 and vessel 56 are completely filled with absorption liquid, the level in absorber 61 is at the upper end of conduit 72. Under these conditions, when heat is applied to the coil 65, the pressure in vessel 68 can be increased. This pressure increase in vessel 68 is transmitted through conduit 71 to the vessel 56 where it acts upon the absorption liquid contained therein so as to press this liquid through U-shaped conduit 63 into the conduit 62 from whence it may flow by gravity into absorber 61, thus raising the

level of the liquid therein sufficiently for flow to take place into the upper end of conduit 72. Liquid will therefore be supplied to coil 40 and refrigerant vapor condensed in the condenser 43 from which liquid refrigerant flows through conduit 44 to the first section 45 of the evaporator. The introduction of this liquid refrigerant into the evaporator 46 displaces an equal volume of absorption liquid from the evaporator through conduit 55 to vessel 56, where it is returned in the manner just described to the absorber. During each heating or vapor expulsion period of the intermittent system, a certain amount of absorption liquid will in this manner be displaced from the evaporator 46 until finally it is all removed.

It will now be understood that with the improved circuit arrangement provided in the intermittent system, the production of refrigeration at the conclusion of a vapor expulsion period can be effectively controlled. When the need for more refrigeration than that produced by evaporator 18 of the continuous system exists, the coil 65 may be heated to initiate a period of refrigerant evaporation. The heating of coil 65 may be continued until the evaporator 46 is depleted of liquid, thereby terminating the refrigerant evaporation period; or coil 65 may intermittently be heated to produce comparatively short periods of intense refrigeration to supplement the refrigeration produced by the continuous system.

If desired, the ejector 77 may be omitted and the lower end of conduit 70 connected to the lower end of the absorber 61. In such case the burner 13 must be shut off when heating element 66 is energized, since liquid can then flow from absorber 61 into generator 40 when the liquid level rises with absorption of refrigerant vapor. Even in such case, however, the refrigerating effect produced by the evaporator 46 of the intermittent system may be so much greater than that produced by evaporator 18 of the continuous system to take care of a normal load, whereby the intermittent system can be arranged to take care of peak loads and the continuous system arranged to take care of the normal load.

The generator 10 of the continuous system and the generator 40 are preferably so tied together that the transfer of heat from generator 10 to coil 40 does not appreciably effect the operation of the continuous system. The transfer of heat to coil 40 may be made relatively small, so that the heating or vapor expulsion period of the intermittent system may be as long as 8 to 10 hours, for example. This can readily be effected by properly dimensioning the generator 10 and coil 40. With this arrangement only a small amount of heat is transferred per unit of time from generator 10 to absorber 61.

Although a single embodiment of the invention has been shown and described, such variations and modifications are contemplated as fall within the true spirit and scope of the invention, as pointed out in the following claims.

What is claimed is:

1. Refrigeration apparatus including a first heat operated refrigerating system and a second heat operated refrigerating system having alternate periods of expulsion of refrigerant from absorbent and evaporation of refrigerant, a common source of heat for said systems, means other than said source of heat for controlling the periods of refrigerant evaporation of said second system, and means embodied in said second system where- by the periods of refrigerant evaporation can take place even when said source of heat is supplying heat to said first system.
2. Refrigeration apparatus comprising a system having alternate periods of expulsion of refrigerant from liquid absorbent and evaporation of refrigerant, said system including an evaporator and an absorber and inter-connecting conduit means therebetween providing a first connection between the vapor space of said absorber and the vapor space of said generator and a second connection between the vapor space of said evaporator and the absorber below the liquid level therein, said first connection including a trap normally clear of liquid at the conclusion of a refrigerant expulsion period whereby the vapor spaces of said absorbent and said evaporator have communication and are at substantially the same pressure whereby evaporation of refrigerant is prevented, and means to cause blocking liquid to flow in said trap and also effect a reduction in absorber pressure whereby the vapor spaces of said absorber and said evaporator are no longer in communication through said first connection and refrigerant vapor flows from said evaporator through said second connection to said absorber to initiate a refrigerant evaporation period.
3. Refrigeration apparatus as set forth in claim 2 in which said refrigerant evaporation period stops when said means to cause blocking liquid to flow in said trap is rendered inoperative and said trap is again free of liquid.
4. Refrigeration apparatus including a first heat operated refrigeration system having a heat receiving part and a second heat operated refrigeration system having a heat receiving part and operating with alternate periods of expulsion of refrigerant from absorbent and evaporation of refrigerant, the heat receiving parts of said systems being in heat exchange relation, means other than said source of heat for controlling the periods of refrigerant evaporation of said second system, and means to block off flow of absorption liquid in said second system whereby the periods of refrigerant evaporation can take place even when said source of heat is supplying heat to said heat receiving parts.
5. An intermittent absorption refrigerating system including an absorber, an evaporator, a conduit connecting the vapor space of said evaporator and said absorber below the liquid level therein, a conduit connecting the vapor space of said evaporator and the vapor space of said absorber, the last mentioned conduit being arranged to have a trap, and means for introducing liquid into and withdrawing liquid from said last mentioned conduit to seal and unseal said trap.
6. An intermittent absorption refrigerating system including an absorber, an evaporator, a conduit connecting the vapor space of said evaporator and said absorber below the liquid level therein, a conduit connecting the vapor space of said evaporator and the vapor space of said absorber, the last mentioned conduit being arranged to have a trap, and means for withdrawing liquid from said absorber and introducing it into said last mentioned conduit to seal said trap and withdrawing liquid from said conduit to unseal said trap.
7. An intermittent absorption refrigerating system including an absorber, an evaporator, a conduit connecting the vapor space of said evaporator and said absorber below the liquid level therein, a conduit connecting the vapor space of said evaporator and the vapor space of said absorber.

sorber, the last-mentioned conduit having a pair of vertically extending legs joined at their lower ends to provide a trap, the vertical extent of said legs being greater than the liquid head in the first-mentioned conduit, and means for introducing liquid into and withdrawing liquid from said legs to seal and unseal said trap.

8. An intermittent absorption refrigerating system including an absorber, an evaporator, a conduit connecting the vapor space of said evaporator and said absorber below the liquid level therein, a conduit connecting the vapor space of said evaporator and the vapor space of said absorber, the last-mentioned conduit having a pair of vertically extending legs joined at their lower ends to provide a trap, a vessel, a conduit connecting the lower part of said vessel with said legs, and means for supplying liquid under pressure to said vessel to establish a liquid seal in said trap.

9. An intermittent absorption refrigerating system including an absorber, an evaporator, a conduit connecting the vapor space of said evaporator and said absorber below the liquid level therein, a conduit connecting the space of said evaporator and the vapor space of said absorber, the last-mentioned conduit having a pair of vertically extending legs joined at their lower ends to provide a trap, a vessel, a conduit connecting the lower part of said vessel with said legs, and a thermosiphon pump for withdrawing liquid from said absorber and supplying it to said vessel under excess pressure for establishing a liquid seal in said trap.

10. Refrigeration apparatus including a continuous refrigerating system having a heat receiving part and an evaporator, a source of heat for said heat receiving part, an intermittent absorption refrigerating system having a second evaporator and a generator arranged to be heated by said source of heat whereby a refrigerant expulsion period takes place during operation of said continuous system, an absorber, a conduit connecting the vapor space of said second evaporator and said absorber below the liquid level therein, a conduit connecting the vapor space of said second evaporator and the vapor space of said absorber, the last-mentioned conduit being arranged to have a trap, and means for introducing liquid into said last-mentioned conduit to seal said trap to initiate a refrigerant evaporation period of said intermittent system.

11. Refrigerating apparatus including an absorption refrigerating system having a generator, condenser, evaporator, absorber and conduits interconnecting the aforementioned parts, an intermittent absorption refrigerating system having a generator, condenser, evaporator, absorber and conduits interconnecting the aforementioned parts, a heater for heating both of said generators whereby a refrigerant expulsion period of said intermittent system takes place during operation of said first-mentioned system, and means independent of said heater for effecting a refrigerant evaporation period of said intermittent system.

12. Refrigeration apparatus including an ab-

sorption refrigerating system having a generator, condenser, evaporator, absorber and conduits interconnecting the aforementioned parts, an intermittent absorption refrigerating system having a generator, condenser, evaporator, absorber and conduits interconnecting the aforementioned parts, the last-mentioned evaporator having a substantially greater refrigerating capacity than the evaporator of said first-mentioned system, a heater for heating both of said generators whereby a refrigerant expulsion period of said intermittent system takes place during operation of said first-mentioned system, and means for effecting a refrigerant evaporation period of said intermittent system during an inactive period of said first-mentioned system to produce an increase in refrigerating capacity.

13. Refrigerating apparatus including a first absorption refrigerating system having a generator, condenser, evaporator, absorber and conduits interconnecting the aforementioned parts, an intermittent absorption refrigerating system having a generator, condenser, evaporator, absorber and conduits interconnecting the aforementioned parts, common means for heating both of said generators whereby a refrigerant expulsion period of said intermittent apparatus takes place during operation of said first-mentioned system, one of said conduits through which liquid flows from said absorber to said generator of said intermittent system communicating with said absorber so as to cut off flow to said generator when the level in the absorber drops below the upper end of said conduit to terminate a vapor expulsion period of said intermittent system, and means to control the refrigerant evaporation period of said intermittent system.

14. Refrigeration apparatus including a heat operated continuous refrigerating system and an absorption refrigerating system of an intermittent type, means for supplying heat to the first-mentioned system at a substantially constant rate in order to produce refrigeration at a substantially constant rate and simultaneously supplying heat to said intermittent system to effect refrigerant expulsion period therein, and means for initiating a refrigerant evaporation period in said intermittent system upon an increase in demand for refrigeration.

15. An absorption refrigerating system of an intermittent type having a generator, a condenser, an absorber, an evaporator and interconnecting conduits including conduits connecting the vapor space of said evaporator to both the liquid and vapor spaces of said absorber, means for heating said generator to expel refrigerant vapor from absorber, condense the refrigerant in said condenser, and flow the liquid refrigerant to said evaporator, and means operable upon a demand for refrigeration for shutting off flow of absorber to said generator and segregating the vapor space of said evaporator and the vapor space of said absorber to cause flow of refrigerant vapor from said evaporator into contact with absorber in said absorber.
